United States Patent Office

Des. 212,696

Patented Nov. 12, 1968

212,696

GAME DEVICE OR SIMILAR ARTICLE

John S. Minarovich, Garland, Tex., assignor to Jole Enterprises Incorporated, Dallas, Tex., a corporation of Texas

Filed July 28, 1967, Ser. No. 8,045

Term of patent 14 years

(Cl. D34—5)

The sole figure is a perspective view of the game device or similar article, the rear and far side being conventionally plain. The numerals located in the windows of the device are indicated by means of broken lines for illustrative purposes only.

I claim:

The ornamental design for a game device or similar article, substantially as shown and described.
